MOTOR-DRIVEN SHAVER OR HAIR CLIPPER

John W. Halterman, Los Angeles, Calif.

Application December 27, 1950, Serial No. 262,851

4 Claims. (Cl. 30—43)

1

This invention relates generally to an electric motor driven safety shaver or hair clipper of the type which includes a pair of very thin flat blades disposed in face to face engagement; the blades having cooperating rows of forwardly projecting cutter teeth on their front edges, and one blade being reciprocated relative to the other at a high speed, whereby to effect the desired cutting or shearing action between said teeth.

This application is a continuation, as to all common subject matter, of copending application Serial No. 12,360, filed March 1, 1948, on Shaver-Clipper.

A major object of the present invention is to provide a shaver or hair clipper, of the type described, in which the pair of cooperating blades are readily removable from the device for the purpose of replacement when worn.

Another important object of this invention is to initially assemble—i. e. at the time of manufacture and before distribution—each pair of cooperating blades in a retaining clip, one blade being fixed in the clip and the other blade being reciprocable in—but non-removable from—the clip, so that said clip and blades are adapted to be mounted in the device as a unit. In other words, when the blades in the device are worn, it is only necessary to release and remove the clip and retained blades, and to reinsert another clip holding new blades.

A further object of the invention is to provide a novel arrangement of elements for properly locating the cooperating blades in the retaining clip, and to similarly locate the clip in the retention head assembly of the device.

A still further object of the instant invention is to construct the blade retaining clip, and the retention head assembly, so that upon insertion of the clip in the latter, effective working contact is maintained between the blades, yet without undue friction therebetween, whereby said blades—when relatively reciprocated—run cool, yet shave or clip hair cleanly.

Still another object of the invention is to provide a shaver or hair clipper, as above, wherein the blade retaining clip, and the retention head assembly, are relatively simple in structure, and compact; the entire device being of relatively small size, light weight, and conveniently hand supported for use.

An additional object of the invention is to provide a motor driven shaver or hair clipper which is designed for ease and economy of manufacture.

Still another object of the invention is to pro-

vide a practical and reliable motor driven shaver or hair clipper, and one which will be exceedingly effective for the purpose for which it is designed.

These objects are accomplished by means of such structure and relative arrangement of parts as will fully appear by a perusal of the following specification and claims.

In the drawings:

Fig. 1 is a perspective view of the novel motor driven shaver or hair clipper.

Fig. 2 is a fragmentary end elevation showing the retention head assembly with a blade retaining clip in place for use.

Fig. 3 is a fragmentary perspective view showing the retention head assembly with the hold-down bar and blade retaining clip removed.

Fig. 4 is an enlarged fragmentary rear elevation of the retention head assembly.

Fig. 5 is a perspective view of the blade retaining clip as manufactured for use, but detached from the device.

Fig. 6 is an enlarged exploded view of the blade retaining clip, and hold-down bar.

Fig. 7 is an enlarged fragmentary sectional elevation of the retention head assembly and blade retaining clip; the view being taken on line 7—7 of Fig. 2.

Referring now more particularly to the characters of reference on the drawings, the novel, motor driven shaver or hair clipper comprises a relatively small, conveniently hand-supported case 1, which may be of suitable material such as plastic, and which case 1 houses an electric drive motor (not shown) of any suitable type, such as is conventionally used in electric shavers.

In the main body thereof the case 1 is generally rectangular in cross section, being rounded at the corners for convenience of handling; such case 1 being elongated, and at its upper end reducing in configuration to a neck 2 which is full-width but narrow from front to back. The current supply cord 3 which energizes the electric drive motor enters the case 1 through its lower end.

At the upper end of the neck 2 the same is formed with a flat elongated base 4 which extends from side to side of said neck; there being a forwardly projecting lip 5 on the neck which increases the effective width of said flat base 4.

The neck 2 is formed with a central longitudinal slot 6, and an actuator pin 7 projects upwardly through such slot; the pin being oscillated at relatively high speed in said slot, lengthwise thereof, from the electric drive motor in

the case. The mechanism by means of which this is accomplished is conventional.

At the upper end of the neck 2, and including the flat elongated base 4, the device embodies a retention head assembly, indicated generally at 8, constructed as follows:

A distance rearwardly of the central longitudinal slot 6, the neck 2 is formed with a deep longitudinal groove 9 which extends from side to side of said neck, whereby to define an up-standing retention or back wall 10. The retention wall 10 is of a height such that its upper edge 11 is disposed above the flat elongated base 4.

A longitudinal hold-down bar 12, having the upper portion of its front edge rounded, as at 13, normally overlies the flat elongated base 4, with the rounded front edge 13 disposed rearwardly of the lip 5.

At its rear edge the longitudinal hold-down bar is formed integral with a depending attachment plate 14 which extends downwardly in close matching but vertically adjustable relation into the deep longitudinal groove 9. The attachment plate 14 is formed, at spaced points in the length thereof, with notches 15 which open to the lower edge of said plate; there being headed screws 16 extending through the retention wall 10 and notches 15, and being threaded into the neck 2. Upon tightening of the headed screws 16, the attachment plate 14 is effectively clamped in the deep longitudinal groove 9, whereby to maintain the longitudinal hold-down bar 12 in a selected position of vertical adjustment.

The numeral 17 indicates generally a longitudinal, blade retaining clip which—when the device is in use—is engaged between the flat elongated base 4 and the hold-down bar 12, as clearly shown in Figs. 1, 2, and 7.

The longitudinal blade retaining clip 17 and the blades therein, as shown in detail in Figs. 5 and 6, are constructed and assembled as follows:

The clip 17 comprises a flat, top wear plate 18 and a flat, bottom wear plate 19 which extend longitudinally in adjacent but spaced parallel relation; said wear plates 18 and 19 being connected, at their rear edges, by an integral web 20, the plates, as so connected, being resilient relative to each other.

A pair of thin flat blades are disposed in face to face engagement and are confined in the clip 17 between and in close relation to the wear plates 18 and 19; said blades being indicated at 21 and 22. The blades 21 and 22 are rectangular in plan and elongated, matching each other in plan, and are of a width such that they project, at their forward edge portions, some distance ahead of the corresponding edges of the wear plates 18 and 19. At their forward edge portions the blades 21 and 22 are formed with rows of cutter teeth, indicated at 23 and 24, respectively. The rows 23 and 24 of cutter teeth are flat and in close matching relation on their inner or adjacent faces; the outer faces of said rows being chamfered, as shown, with the row 23 terminating at its front edge adjacent, but short of, the front edge of the row 24.

The upper blade 21 is the reciprocating one, while the lower blade 22 is the stationary one; the blade 22 having a central longitudinal slot 25 through which the actuator pin 7 projects upwardly when the clip 17 is in place. The

blade 21 includes a central, circular opening 26 which receives the upper end of the actuator pin 7 with a matching fit.

With this arrangement the actuator pin 7, projecting through the slots 6 and 25 and engaging in the opening 26, oscillates the upper blade 21 lengthwise and at relatively high speed, whereupon the row of cutter teeth 23 cooperates with the row of cutter teeth 24 to produce the desired cutting or shearing action for shaving or hair clipping; said cooperating rows of cutter teeth projecting ahead of the lip 5 for close engagement with the flesh.

The reciprocating blade 21 and the stationary blade 22 are properly located in the retaining clip 17, with the blade 21 guided for reciprocating motion, in the following manner:

The blades 21 and 22 are formed, at each end, with rectangular end notches 27 and 28, respectively; said notches registering, except that the notches 27 are of greater length.

At each end thereof the top wear plate 18 is formed with a pair of longitudinal, transversely spaced, depending blade locating flanges 29 which engage downwardly through the corresponding notches 27 and 28 of the blades 21 and 22, effectively locating said blades in the clip 17. However, as the notches 27 are elongated and of greater length than the depending blade locating flanges 29, the blade 21 may reciprocate while remaining properly located by such flanges.

When assembling the clip and blades as a unit at the factory, the plates 18 and 19 are initially disposed at an angle sufficient to enable the blade notches to be slipped over the flanges 29 so as to locate the blades in the clip, and said clip is then placed in a press to force the plates together to properly position them relative to the blades and to each other.

40 The material from which the clip is made is a metal having sufficient rigidity and strength to resist spreading and deformity when once the clip plates are pressed together, so that the blades disposed between the plates are non-removable relative to the clip for all practical purposes.

45 The bottom wear plate 19 is formed at each end with a pair of longitudinal, transversely spaced, depending clip locating flanges 30 which removably seat in rectangular end notches 31 formed in the base 4. With the pairs of flanges 30 seating in the notches 31, the clip 17 is located on the base 4 in proper relation to the actuator pin 7, and with the rear edge of said clip 17 abutting against the depending attachment plate 14; the hold-down bar 12 bearing on top of the clip 17 when the device is in use.

50 After the blades 21 and 22 in a clip 17 have become worn, the headed screws 16 are loosened and the attachment plate 14 is slid upwardly until the hold-down bar 12 is raised some distance above the clip; i. e. a distance greater than the depending length of the locating flanges 30.

55 The clip 17 is then merely raised until the flanges 30 escape the notches 31, and the actuator pin 7 escapes the opening 26, whence the clip is freely withdrawn and discarded.

60 A new clip 17 is then disposed on the base 4, with its locating flanges in the notches 31, and with the actuator pin 7 in the opening 26 of the reciprocating blade 21.

65 Thereafter, the hold-down bar 12 is lowered into engagement with the clip 17 and manually depressed against the top wear plate 18 to a degree such that the blades 21 and 22 are main-

tained in effective working contact between the wear plates 18 and 19, but without undue friction.

The headed screws 16 are then tightened, which locks up the retention head assembly 8, and the device is ready for use.

By reason of the fact that the hold-down bar 12 can be conveniently adjusted, it is easy to vary the pressure exerted on the blades 21 and 22 to maintain them in effective working contact, and which variance of pressure may be desirable to compensate for slight wear, etc.

The wear plates 18 and 19 are formed of a metal which produces a minimum of friction with the blades 21 and 22, the latter preferably being an alloy steel.

Also, if desired, a permanent type of lubricant may be filmed between the relatively moving parts of the clip 17 and the blades therein.

It is contemplated that the blade retaining clips 17 will be packaged in multiple so that a user may have on hand extra clips for use when the occasion demands; the removal and replaceable clip feature of the device making it most desirable and convenient in use.

Also, by reason of the particular mounting of the blades in the clip, with the ability to alter the pressure on said blades to maintain effective working contact at all times, the device serves most effectively, either as a shaver or hair clipper.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A blade retaining clip for a power driven shaver or hair clipper having a flat base and a driven oscillating element provided with a driving end exposed above said base, said clip comprising elongated upper and lower wear plates disposed in adjacent but spaced relation, an integral web connecting said plates along one edge in resilient relation, flat elongated upper and lower blades disposed in face to face engagement between the wear plates, the cooperating longitudinal working edges of the blades projecting beyond the edges of the wear plates opposite said web, means relatively slidably mounting the blades between the plates and including, with longitudinally disposed notches registering with each other in the ends of the blades, locator flanges on one wear plate projecting into said registering notches and contacting the longitudinal walls thereof; the locator flanges also contacting the ends of the notches in one of said blades and holding said one blade stationary in the clip, the notches in the other blade being elongated relative to said locator flanges to permit said other blade to reciprocate lengthwise relative to said locator flanges; said other blade

having an opening intermediate its ends adapted to receive the driving end of said oscillating element in driving relation when the clip is mounted on the base; said one blade having an elongated slot through which the oscillating element projects in clearance and non-driving relationship.

2. A removable blade and clip unit for an electric shaver comprising a pair of flat cooperating blades, a substantially rigid clip embracing and retaining the blades in substantial contact with each other and comprising upper and lower plates terminating short of the front working edges of the blades, and an integral web connecting the plates at the back and preventing normal separation thereof, and elements on one plate projecting through notches in the blades; the notches in one blade being of a width and length such that the side and end edges thereof engage said elements in a manner to prevent lateral and longitudinal displacement of said blade, while the notches in the other blade are of a width thereof relative to the elements such that the longitudinal edges of said notches substantially engage the elements to prevent lateral displacement of said other blade while the distance between the inner end of the notches is greater than the distance between the elements so as to allow of longitudinal reciprocating movement of said other blade relative to the one blade.

3. In a power driven shaver or clipper having a base and an oscillating actuating pin projecting from the base; a removable blade unit comprising a pair of blades disposed in cooperating relation and a substantially rigid clip comprising upper and lower plates between which the blades are confined in relatively reciprocable relation and having a back web integral with said plates, the blades having longitudinal working edges projecting from the clip, elements on one plate engaging the blades to normally retain the latter in the clip against removal in directions endwise of and forwardly out from the clip, and means to removably mount the clip on the base; one blade having an opening to receive the actuating pin in driving relation to reciprocate said one blade.

4. A device, as in claim 3, including means to locate the clip in a predetermined position on the base, said last named means comprising elements rigid with and depending from the clip at its ends, the base having recesses to receive said elements.

JOHN W. HALTERMAN.
